UNITED STATES PATENT OFFICE

2,151,526

TELEVISION APPARATUS

Waldemar J. Poch, Collingswood, N. J., assignor
to Radio Corporation of America, a corpora-
tion of Delaware

Application October 31, 1935, Serial No. 47,552

7 Claims. (Cl. 178—7.5)

In invention relates to television apparatus and particularly to a method of and means for separating picture signals from synchronizing impulses.

5 In British Patent No. 407,409 there is described a television system in which scanning at the receiver is maintained in synchronism with scanning at the transmitter by transmitting a horizontal synchronizing impulse of short duration at the end of each scanning line and a vertical impulse of the same amplitude and longer duration at the end of each picture frame. The synchronizing impulses are of greater amplitude than the picture signals and preferably are in the 10 "black" direction. An improved system for transmitting a composite signal of this character is described in application Serial No. 728,147, filed May 29, 1934, in the name of A. V. Bedford, and assigned to the Radio Corporation of America.

15 At the receiver, the picture signals and the synchronizing impulses are separated from each other before the synchronizing impulses are impressed upon the horizontal and vertical deflecting circuits. Various circuits have been proposed 20 for obtaining this separation, each circuit having some particular advantage over the others.

An object of my invention is to provide an improved separating circuit of the above-mentioned type which supplies synchronizing impulses of 25 comparatively large amplitude.

A further object of my invention is to provide an improved separating circuit for separating positive polarity synchronizing impulses from picture signals.

30 A still further object of my invention is to provide an improved separating circuit which will operate to give good separation even though the signals and impulses are varying in amplitude.

In a preferred embodiment of my invention, I 35 employ an electric discharge tube having a negatively biased control grid. Instead of applying voltage to the plate of this tube through a plate resistor of the usual resistance value, I apply voltage to the plate through a resistor having such high resistance that, with no signal on the grid, the plate voltage is so low that the tube is operating near the cut-off point. Each time a 40 positive synchronizing impulse is impressed upon the control grid, the plate current increases slightly to lower the plate voltage further whereby the tube is biased beyond cut-off and only the positive synchronizing impulses appear in the tube output.

Other objects, features and advantages of my 45 invention will appear from the following descrip-

tion taken in connection with the accompanying drawings in which—

Figure 1 is a circuit diagram of one embodiment of my invention;

Fig. 2 is a circuit diagram of another embodiment of my invention;

Fig. 3 is a set of curves which are referred to in explaining the operation of the circuits shown in the preceding figures; and

Fig. 4 is a circuit diagram of still another embodiment of my invention.

Referring to Fig. 1, there is illustrated a television receiver which is designed to receive picture and synchronizing impulses which have been transmitted by means of a modulated carrier wave 15 in accordance with the teachings of the above-mentioned British patent or Bedford application. The receiving apparatus includes a radio receiver 1 which selects and demodulates the desired carrier wave whereby picture signals and 20 synchronizing impulses of the character described above appear in the output circuit thereof.

The picture signals and synchronizing impulses are amplified in a signal channel including resistance coupled amplifiers 2 and 3 and are impressed upon the control grid 4 of a cathode ray tube 6. The cathode ray tube 6 may be of well known construction comprising an evacuated envelope having therein a cathode 7, the control grid 4, a first anode 8, and a second anode 9. 30 Suitable deflecting means, such as deflecting coils 11 and 12 are provided for deflecting the cathode ray both horizontally and vertically to effect scanning of a fluorescent screen 13 at the end of the tube.

The horizontal deflecting coils 11 are supplied with saw-tooth current having comparatively high frequency from a horizontal deflecting circuit 14. The vertical deflecting coils 12 are supplied with saw-tooth current having a comparatively low frequency from a vertical deflecting circuit 16.

The number of amplifier stages in the radio receiver 1 is so selected that the polarity of the synchronizing impulses impressed upon the control grid 4 of the cathode ray tube 6 is negative whereby the cathode ray is blocked at the end of each scanning line, this being desirable in order to prevent a trace on the fluorescent screen during the return line period.

The scanning of the fluorescent screen 13 by the cathode ray is maintained in synchronism with the scanning at the transmitter by separating the synchronizing impulses from the picture

signal and impressing these impulses upon the deflecting circuits 14 and 18.

The separation of the picture and synchronizing signals preferably is accomplished by means 5 of a circuit comprising an electric discharge tube 17 having a cathode 18, a control grid 19 and a plate 21. The control grid 19 is negatively biased from a suitable biasing source, such as a battery 22, which is connected between the cathode 10 18 and the control grid 19, through a grid resistor 23. It will be understood that with certain types of tubes the control grid may be operated with a zero bias. Signals are supplied to the control grid 19 through a coupling condenser 24, 15 these signals being derived from the output circuit of the amplifier tube 2 wherein the synchronizing impulses are of positive polarity.

In accordance with my invention, a positive operating voltage is applied to the plate 21 through 20 a resistor R_3 , which has a comparatively high resistance value. The resistor R_3 is by-passed by means of a suitable by-pass condenser 26.

The resistor R_3 has such high resistance that, with the negative bias being applied to the control grid 19, the tube 17 is biased almost to the cut-off point. This will be seen by referring to Fig. 3 in which the curve 27 represents the grid voltage-plate current characteristic of the tube 17, where the plate voltage has the value corresponding to the condition of no signal on the control grid. As indicated by the dotted line 28, and the legend "grid bias", the tube 17 is biased almost to cut-off whereby the flow of plate current is small.

35 The curve 29 in Fig. 3 is a simplified curve representing a mixture of picture signals and synchronizing impulses. The portions indicated at 31 and 32 are referred to as the "pedestals", the top of the "pedestals" at a and b representing 40 "black". On the top of each pedestal there is a synchronizing impulse proper, which is frequently referred to as the "super-sync impulse", these impulses being indicated at 33 and 34.

It will be evident that as soon as the synchronizing impulses are impressed upon the control grid 19, they will make the control grid less negative and each impulse will cause a momentary increase in the flow of plate current through resistor R_3 . The resulting voltage drop in R_3 causes a reduction in voltage applied to the plate 21. The grid voltage-plate current characteristic of the tube for the value of plate voltage resulting from impulse 33 is represented by the curve 36. As indicated by the dotted line 37, the 55 result is that only the "super-sync impulse" appears in the output circuit of the tube 17 as shown at 38.

The synchronizing impulses which appear across the resistor R_2 are supplied through a coupling condenser C_3 to suitable separating circuits which separate the horizontal synchronizing impulses and the vertical synchronizing impulses to supply each group of impulses to the proper deflecting circuit. The horizontal separating circuit includes a condenser 41 and resistor 42 in series, the condenser 41 having such small capacity that only the comparatively high frequency horizontal synchronizing impulses appear across the resistor 42 to be impressed upon the horizontal deflecting circuit 14. The vertical separating circuit includes a resistor 43 and condenser 44 in series, the condenser 44 having a comparatively large value, whereby only the comparatively low 75 frequency vertical synchronizing impulses ap-

pear across it to be impressed upon the vertical deflecting circuit 18.

It will be seen that my improved picture signal and synchronizing impulse separating circuit does not depend for its operation upon the flow 5 of grid current and that, as a result, the input impedance of the tube 17 is always fairly high and it is possible to obtain good amplification of the synchronizing impulse.

It has previously been proposed to separate picture signals from synchronizing impulses by means of an ordinary amplifier tube biased beyond the cut-off point. Such a circuit is satisfactory in operation, providing there is not too great variation in the amplitude of the synchronizing impulses. It has been found that there 10 usually is a considerable variation in the amplitude of synchronizing impulses and one of the 15 main advantages of the present separating circuit is that it will provide good separation regardless of this variation in amplitude.

From the foregoing description it will be understood that the more positive the control grid 19 is made, the greater will be the flow of plate current and (referring to Fig. 3) the farther the 25 cut-off point of the tube will be moved to the right. Thus, in Fig. 3, the second pedestal 32 is shown as having greater amplitude than the first pedestal, whereby the control grid 19 is driven more positive than formerly to produce an increase 30 in plate current flow. The resulting reduction in plate voltage gives the tube 17 a characteristic curve such as indicated at 46, the cut-off point being moved still farther to the right. As indicated by the dotted line 47, the cut-off 35 point has been moved to a position such that only the "super-sync impulse" 34 appears in the output of the tube, as indicated at 48.

In Fig. 2 there is illustrated a variation of the invention shown in Fig. 1. Corresponding parts 40 in Figs. 1 and 2 have been indicated by the same reference characters. In this embodiment of the invention, the high plate resistance is employed, as previously described, whereby the only current flowing through the resistor R_3 will be that corresponding to the peaks of the positive synchronizing impulses. The voltage appearing across the resistor R_3 is impressed upon a second amplifier tube 51 through a coupling condenser 50.

The resistance value of the resistor R_3 is determined by the considerations previously discussed. The resistor R_2 may have a value substantially the same as the value of the corresponding element in Fig. 1, the values of condenser 50 and resistor R_2 being selected to give the amplifier circuit the required high frequency response to permit the passage of the sharp, high frequency synchronizing impulses.

As illustrated in Fig. 4, a screen grid tube may be employed in place of a three element tube by supplying voltage to the screen grid through a resistor having a high resistance value. This is possible since a change in the screen grid voltage of a screen grid tube has substantially the same effect upon the control grid voltage-plate current 65 characteristic curve as does a change in the plate voltage of a three element tube. Corresponding parts in Figs. 1 and 4 are indicated by the same reference characters.

It will be noted that in Fig. 4 the screen grid 70 voltage is applied through a high resistance resistor R_3 while the plate voltage is applied through a comparatively low resistance resistor R_2 . In operation, a positive synchronizing impulse causes an increase in screen grid current 75

whereby the voltage drop across R_3 increases to lower the screen grid voltage. This causes the screen grid tube to be biased beyond cut-off with the result that only synchronizing impulses appear across the plate resistor R_2 .

5 The values of the various circuit elements in Figs. 1, 2 and 4 are not at all critical. For example, while a value of two megohms has been found very satisfactory for the resistor R_3 , this 10 resistor may be given a value as low as one-half megohm, or as high as several times two megohms. The values of various elements are indicated on the drawings in ohms, megohms and microfarads. It will be understood that the 15 values are given merely by way of example and may be varied within wide limits.

It will be apparent from the foregoing description that various modifications may be made in my invention, without departing from the 20 spirit and scope thereof and I desire, therefore, that only such limitations shall be imposed thereon as are necessitated by the prior art and are set forth in the appended claims.

I claim as my invention:

25 1. In a television receiver for the reception of a composite signal comprising picture signals and synchronizing impulses, said impulses having a greater amplitude than picture signals of like polarity, an electric discharge tube having 30 a control grid and a plurality of other electrodes, said tube having the characteristic that its cut-off point is changed in response to a change in voltage on one of said other electrodes, a resistor, means for applying a positive voltage to 35 said one electrode through said resistor which has such high resistance that a slight increase in current therethrough causes a substantial change in said cut-off point, means for so biasing said grid that the tube is close to cut-off 40 when there is no signal on said grid, and means for impressing said composite signal upon said grid with the said impulses having a positive polarity.

2. The invention according to claim 1 characterized in that said tube is of the three-element 45 type and further characterized in that said one electrode is the plate of said tube.

3. The invention according to claim 1 characterized in that said tube is of the screen grid 50 type and further characterized in that said one electrode is the screen grid of said tube.

4. In a television receiver for the reception of

a composite signal comprising picture signals and synchronizing impulses, said impulses being of greater amplitude than said signals, means for separating said impulses from said signals, said means comprising an electric discharge tube of 5 the three element type having a cathode, a control grid, and a plate, a resistor having a comparatively high resistance, means for applying a positive potential to said plate through said resistor whereby the plate voltage decreases in 10 response to an increase in plate current through said resistor, means for maintaining said grid at a bias potential such that the tube is close to the cut-off point when there is no signal on said grid, and means for impressing said composite 15 signal upon said grid with the synchronizing impulses in the positive direction, the resistance of said plate resistor being so great that said impulses cause a voltage drop across said resistor sufficient to bias said tube beyond cut-off. 20

5. In a television receiver for the reception of a composite signal comprising picture signals and synchronizing impulses, said impulses having a greater amplitude than picture signals of like polarity, an electric discharge tube of the three 25 element type having a plate and a control grid, a resistor having a resistance at least as great as one-third megohm, means for applying voltage to said plate through said resistor, means for so biasing said grid that the tube is close 30 to cut-off when there is no signal on the grid, and means for impressing said composite signal upon said grid with the said impulses having a positive polarity. 35

6. The invention set forth in claim 4 characterized in that a resistor of comparatively low resistance is connected between said plate and said first resistor and in series therewith, and further characterized in that the receiver includes means for utilizing the synchronizing impulses appearing across said low impedance resistor. 40

7. The invention set forth in claim 5 characterized in that a resistor of comparatively low resistance is connected between said plate and said first resistor and in series therewith, and further characterized in that the receiver includes means for utilizing the synchronizing impulses appearing across said low impedance resistor. 45
